SIMPLEX STREET GUIDE

Herbert Meyer and Edna M. Spiegel, New York,
N. Y., assignors to Nicholas Meyer, New York,
N. Y.

Application January 29, 1942, Serial No. 428,705

5 Claims. (Cl. 40—130)

This invention relates to street guides.

An object of this invention is to provide an illuminated street guide comprising a glass container shaped in the form of a flattened arrow or pointer, and having a sign plate therein, and a filament within the container disposed around the edges of the container, so that the filament is shaped like an arrow or pointer so that when the same is illuminated it will point in the direction of the arrow.

A further object of this invention is to provide a sign of the character described which is visible during the day and which can be illuminated at night.

A still further object of this invention is to provide a sign of the character described, having portions disposed in planes at right angles to one another for use at said intersections.

Yet another object of this invention is to provide a compact and durable sign of the character described, which shall be relatively inexpensive to manufacture, and practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is an elevational cross-sectional view through a sign or guide embodying the invention;

Fig. 2 is a cross-sectional view taken on line 2—2 of Fig. 1;

Fig. 3 is a front elevational view of a modified construction with parts broken away, and in cross-section; and

Fig. 4 is a cross-sectional view taken on line 4—4 of Fig. 3.

Referring now in detail to the drawing, 10 designates a street guide or sign embodying the invention. The same comprises a container or casing 11 in the shape of a flattened arrow opened at its rear end. Extending downwardly from the middle of the underside of the casing 11 is an externally screw threaded knob 12.

The casing 11 may be made of glass or other transparent material. It may also be made of transparent or translucent material. Screwed to the nipple 12 is a metal nipple 13 fixed to the

upper end of any suitable tubular traffic standard.

At the rear end of the casing 11 is a hinged closure member or cover 16, hinged as at 17 and provided with a spring catch 18 at its lower end to retain the cover closed. Within the casing is a sign plate 20 which may be made of any suitable heat resisting material. A sign may be painted on opposite sides of the plate 20. The plate 20 may be shaped like an arrow, but with the head narrowed down to the width of the shank, so that the plate may be inserted through the open end of the casing.

Attached to the middle or top of the casing 11 is a second casing 22 substantially similar to casing 11, but disposed at right angles thereto. The casing 22 is likewise open at one end, and has a hinged cover, the same as casing 11. Within casing 22 is also a sign plate 20a, similar to sign plate 20. Casing 22 may be attached to the casing 11 by bolts 23 or by fusing the two casings together. Casing 11 is formed with an opening 25 at the top end thereof communicating with opening 26 at the bottom of casing 22.

Within casings 11 and 22 is a wire or filament 30 which extends all around the edge of the sign plate 20, and passes up through the openings 25, 26 and then around the edge of the sign plate 20a. The filament preferably has the shape of the casings 11 and 22. Said filament is attached to wiring 31 which passes through the nipple 13. The wire or filament 30 may be similar to heat resisting wire used in broilers which will glow when energized.

The casings 11 and 12 are preferably made of heat resisting glass or other material, so as not to be burnt or melted when the wire 30 is heated.

In Fig. 3 there is shown a sign 40 comprising a casing 41 in the shape of a double pointing arrow. The casing 41 may be hermetically sealed. Within said casing is a plate 42 with points at the opposite ends thereof. Extending downwardly from casing 41 is a nipple 43 attached to a movable nipple 44. Within the casing 41 is a filament 47 extending around the inner edge of the casing 41. The filament is attached to wiring 45.

The air has preferably been exhausted from casing 41 and the filament may be somewhat similar to the filament of an incandescent lamp. The filament 47 is preferably somewhat spaced from the inner surface of the casing 41 and the outer edge of plate 42. The casing 41 is preferably transparent and made of heat resisting material. The sign plate 42 may have any suit-

able sign painted or otherwise marked on opposite surfaces thereof, and is also made of heat resisting material.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described our invention, we claim as new and desire to secure by Letters Patent:

1. A street guide comprising a flattened casing, a second flattened casing mounted on the first casing, and disposed at right angles thereto, said casings being made of transparent material, opaque sign plates within said casings, said casings having registering openings, and a conductive resistance filament adapted to glow when electricity passes through it, passing through both casings and around said sign plates, and through said registering openings.

2. A street guide comprising a flattened casing, a second flattened casing mounted on the first casing, and disposed at right angles thereto, said casings being made of transparent material, opaque sign plates within said casings, said casings having registering openings, a conductive resistance filament adapted to glow when electricity passes through it, passing through both casings and around said sign plates, and through said registering openings, said casings each being open at one end, and a cover to close each end of said casings.

3. A street guide comprising a casing having the shape of a flattened arrow, a nipple extending from the middle of the underedge of said casing, said casing being open at its rear end, a cover hinged to said rear end for closing said end of said casing, a sign plate within the casing, and insertable thereinto through the rear end thereof, and a conductive resistance wire adapted to

glow when electricity passes through it passing through said nipple and within said casing and around said sign plate and means to connect said wire to a source of electricity.

4. A street guide comprising a casing having the shape of a flattened arrow, a nipple extending from the middle of the underedge of said casing, said casing being open at its rear end, a cover hinged to said rear end for closing said end of said casing, a sign plate within the casing, and insertable thereinto through the rear end thereof, a wire passing through said nipple and within said casing and around said sign plate, a second casing mounted on the middle of the top of the first casing, and disposed at right angles thereto, the first casing having an opening at the top edge thereof, and the second casing having an opening at the bottom edge thereof registering with the first opening, a sign plate in the second casing, and said filament passing through the registering openings and around the sign plate in the second casing.

5. A street guide comprising a casing having the shape of a flattened arrow, a nipple extending from the middle of the underedge of said casing, said casing being open at its rear end, a cover hinged to said rear end for closing said end of said casing, a sign plate within the casing, and insertable thereinto through the rear end thereof, a wire passing through said nipple and within said casing and around said sign plate, a second casing mounted on the middle of the top of the first casing, and disposed at right angles thereto, the first casing having an opening at the top edge thereof, and the second casing having an opening at the bottom edge thereof registering with the first opening, a sign plate in the second casing, and said filament passing through the registering openings and around the sign plate in the second casing, said second casing being open at its rear end and being provided with a hinged cover to close said rear end, and said second sign plate being insertable into the second casing through the open rear end thereof.
